ATTORNEY

UNITED STATES PATENT OFFICE

169,832

BOOKHOLDER OR SIMILAR ARTICLE

Jefferson P. Waldrop, Jackson, Miss.

Application June 20, 1952, Serial No. 20,289

Term of patent 14 years

(Cl. D33—3)

To all whom it may concern:

Be it known that I, Jefferson P. Waldrop, a citizen of the United States of America, and a resident of Jackson, Mississippi, have invented a new, original, and ornamental Design for a Bookholder or Similar Article, of which the following is a specification, reference being had to the accompanying drawings, forming a part thereof:

Figure 1 is a perspective view of a bookholder or similar article showing my new design,

Figure 2 is a side elevational view thereof,

Figure 3 is a top plan view thereof,

Figure 4 is a front elevational view thereof, and

Figure 5 is a rear elevational view thereof.

I claim:

The ornamental design for a bookholder or similar article, as shown.

JEFFERSON P. WALDROP.
